ADJUSTABLE IRONING BOARD

Roxton C. McKinnie, Santa Monica, Calif.

Application June 18, 1948, Serial No. 33,856

3 Claims. (Cl. 38—121)

1

This invention relates to work-supporting tables such as ironing boards, and more particularly to ironing boards having legs which optionally may be extended to operative position so as to support the body of the ironing board at convenient height, or may be folded to retracted position so that the board can be stored conveniently and within a minimum of space.

The present invention constitutes an improvement over those forming the subject matter of my co-pending applications, Serial Number 704,-641, filed October 21, 1946, now abandoned and Serial Number 767,976, filed August 11, 1947 now Patent No. 2,596,267, dated May 13, 1952.

An object of my present invention is to provide an ironing board having folding legs as hereinabove indicated, and wherein certain of the legs are arranged so that when they occupy their operative position, they are spread apart, and when they assume their folded or retracted position, they are disposed more closely together. Consequently, when the board is in use, it is possessed of a greater degree of lateral stability, and yet when the board is folded, its legs do not occupy a space any wider than does the body of the ironing board.

A further object of the invention is to provide means for automatically spreading the legs as they are unfolded or extended, and for automatically drawing them laterally inwards toward each other as they are folded, with the result that the operator is not required to devote any more attention or effort to adjust the legs to either their operative or their inoperative position than in the case of more conventionally constructed ironing boards not possessed of the spreading legs feature.

Another object is to incorporate the spreading leg feature of the character indicated, with a folding ironing board, the legs of which are movable to any one of a plurality of optionally selectable positions, so as to cause the board to be supported at the precise, selected height which will afford the greatest convenience to its user.

It is a further object of the invention to provide a folding ironing board of the general character indicated, which is simple and inexpensive in construction and which is of relatively light weight, and yet which is possessed of ample strength and rigidity to afford full measure of convenience during use.

The invention possesses other objects and features of advantage, some of which, with the foregoing, will be set forth in the following description of the preferred forms of my invention which are illustrated in the drawings accompanying

5 forms within the scope of my invention as set forth in the claims.

Referring to the drawings:

Figure 1 is a perspective view of a folding ironing board incorporating the principles of the present invention and showing the ironing board, viewed from below, in its extended or operating position.

Figure 2 is an underneath plan view, showing the board in its folded position.

Figure 3 is an enlarged detail view in longitudinal vertical section, taken upon the line 3—3 of Figure 2, with the direction of view as indicated.

Figure 4 is an enlarged detail view, taken in transverse section on the line 4—4 of Figure 2, with the direction of view as indicated.

Figure 5 is an enlarged detail view in oblique vertical section, taken upon the line 5—5 of Figure 2, with the direction of view as indicated.

Figure 6 is a view similar to Figure 1, showing a modified form of folding ironing board in its extended or operative position, incorporating the principles of the present invention.

Figure 7 is a bottom plan view of the ironing board of Figure 6, with its supporting legs in their folded or retracted position.

Figure 8 is a transverse, vertical sectional view, with its plane of section indicated by the line 8—8 of Figure 6 and the direction of view by the arrows, portions of the figure being broken away to reduce its size.

Figure 9 is a detail view in longitudinal, vertical section, taken from the line 9—9 of Figure 8, with the direction of view as indicated. Portions of this figure also are broken away to reduce its size.

Figure 10 is an enlarged detail view in perspective of the latch for releasably and adjustably locking the legs together with the body of the board supported at selected elevation.

Figure 11 is another view similar to Figure 1, showing a still further modified form of folding ironing board in operative position, incorporating the principles of the present invention.

Figure 12 is a bottom plan view of the ironing board of Figure 11, retracted to its folded position.

Figure 13 is a transverse, vertical sectional view taken on the line 13—13 of Figure 11, with the direction of view as indicated, portions of the figure being broken away to reduce its size.

Figure 14 is an enlarged detail view in longitudinal vertical section, taken from the line 14—14 of Figure 13, with the direction of view as indicated. Portions of this figure also are broken away to reduce its size.

Figure 15 is an enlarged detail view in perspective of an alternative form of catch for releasably and adjustably locking the legs of the ironing board to each other so as to support the body at selected elevation.

Figure 16 is a longitudinal, vertical sectional view, the plane of section being indicated by the line 16—16 of Figure 15, with the direction of view as indicated.

Referring first to that modification of my present invention which is illustrated in Figures 1 to 5, inclusive, my improved folding and vertically adjustable ironing board comprises a body 16 of suitable rigid material, either wood or metal, and formed with a broad end 17 and a narrow or substantially pointed end 18 in accordance with conventional practice.

The leg 21 is pivotally secured adjacent its upper end to the under surface of the body 16 preferably by means of a bracket plate 22 having a pair of downturned lugs 23 which are spaced apart by a distance which preferably is at least as great as one-half the width of the body 16. The leg 21 is preferably of compound construction, being formed of a pair of angle members, the lower portions 24 of which are joined together into a single, straight section. About midway of the leg 21, however, the two angle members are deflected outwards so that their upper portions 26 diverge at such an angle that their upper ends are separated by a distance substantially co-inciding with the over-all distance between the two lugs 23 of the mounting plate 22. Axially aligned pins 27 pivotally connect the upper ends of the portions 26 of the leg 21 to these lugs 23.

Two more legs 31 and 32 are disposed in opposition to each other and in a plane which is common to both and which is intersected by the downwardly inclined first-mentioned leg 21. These two legs 31 and 32 constitute a pair of legs, which is indicated at 33, which straddle the single leg 21, as is best shown in Figure 1.

The pair 33 of legs is pivotally connected to the single leg 21 for rotary movement with respect thereto about a transverse axis which is disposed substantially intermediate the ends of the single leg 21 and also intermediate the ends of each of the legs 31 and 32. This is accomplished by means of a transverse rod 36, to the opposite ends of which the legs 31 and 32 are secured, this rod being pivotally mounted for rotation about its own longitudinal axis as by means of a pair of laterally spaced brackets 37 through both of which the rod 36 extends freely. Each of these brackets 37 is carried rigidly by the upper, divergent portion 26 of one of the angle members of which the leg 21 is formed.

The means for connecting the rod 36 to the two legs 33 comprises a pivot pin 38 adjacent each end of the rod 36. These pins 38 extend perpendicularly to the axis of the rod 36 and through the inwardly extending flanges 31', 32' respectively, of the associated legs 31 and 32, thus establishing a pivotal connection between the rod 36 and each of the legs 31 and 32, permitting rocking motion of each of the legs 31 and 32 about an axis perpendicular to the transverse plane which is common to both of the legs 31 and 32. This rocking motion of the two legs 31

and 32 within their said common plane is in addition to the pivotal motion of which both legs 31 and 32 partake about a transverse axis, i. e., about the axis of the rod 36; and permits the upper ends of the legs 31 and 32 to swing toward each other, and their lower ends to spread apart as the legs 21, 31 and 32 are swung downwardly, away from the body 16. Conversely, the upper ends of the legs 31 and 32 move away from each other and their lower ends move toward each other, as the three legs 21, 31, and 32 are swung upwardly, toward the body 16.

The upper ends of the pair 33 of legs are mounted upon the under side of the body 16 for longitudinal movement therealong so as to permit the leg 21 and the pair 33 of legs 31 and 32 to be moved optionally to their extended, operating position, as illustrated in Figure 1; or to their retracted or folded position, as illustrated in Figure 2; or to any of a plurality of optionally selectable intermediate positions so as to support the body 16 at any of a plurality of optionally selectable working positions. This is a feature in common between the ironing board of the present invention and those constituting the subjects matter of my aforesaid co-pending applications, and is one of material importance and convenience inasmuch as it makes it possible for the operator to use the ironing board at that particular elevation which will afford the greatest convenience.

However, in the ironing board of the present invention, the means mounting the upper ends of the legs 31 and 32 for movement longitudinally of the body 16 also guides the upper ends of the legs 31 and 32 in predetermined paths of movement. In the modification of Figures 1 to 5, inclusive, this mounting and guiding means comprises an eye 41 preferably pivotally mounted upon the upper end of each leg 31, 32, as by a transverse pivot pin 42. Each of the eyes 41 is slidable upon a guide rod 43 mounted rigidly upon the body 16 parallel to and spaced slightly below the under surface thereof by means of a mounting plate 44 having downturned end flanges 48 to which the corresponding ends of the associated guide rod 43 are rigidly secured. These mounting plates 44 are secured to the under surface of the body 16 by any suitable means and substantially midway between the mounting plate 22 for the single leg 21 and the pointed end 18 of the body 16.

In the modification of the invention presently being described, these guide rods 43, instead of being straight, are of substantially arcuate form, for a purpose to be explained in detail hereinbelow. The ends 47 of the rods 43 which are nearest the mounting plate 22 for the single leg 21 are substantially parallel to each other and relatively close together; whereas the opposite ends 48 of the rods 43 diverge in substantially arcuate paths, with the result that they are materially more widely separated than are the inner ends 47.

Thus it may be seen that if the lower end 24 of the single leg 21 is swung upwards toward the pointed end 18 of the body 16 from that position in which it is illustrated in Figure 1, this movement will occur about the axis of the aligned pins 27 and will carry the connecting rod 36 upwardly in an arcuate path toward the mid-portion of the body 16. Hence, the intermediate portions of the two legs 31 and 32, to which the ends of the rod 36 are connected, will also be carried upwards in that same arcuate path, causing

the upper ends of the legs 31 and 32 to slide upon their guide rods 43 toward the pointed end 18 and consequently swinging the lower ends of the two legs 31 and 32 upwards toward the wider end of the board 17 at approximately the same rate as the lower end 24 of the single leg 21 moves upwards. This movement of the legs toward the body 16 may be continued until they all lie in a common plane closely adjacent and parallel to the under surface of the body 16, as illustrated in Figure 2, permitting the folded ironing board to be stored away within a minimum of space.

Unfolding or extending the legs 21, 31, and 32 to their operative position is accomplished in the opposite manner, i. e., with the ironing board standing erect and supported upon the lower end of preferably one of the two legs 31, 32, the operator may grasp the pointed end 18 of the body in one hand and the upper end 24 of the single leg 21 in the other hand, and by moving the end 24 away from the body, the leg 21 is caused to rotate about the axis of the pins 27 carrying the rod 36 away from the board in an arcuate path. This draws the midportions of the legs 31 and 32 away from the board, but since their upper ends are restrained against movement away from the board and yet permitted longitudinal movement therealong toward the broad end 17, the lower ends of the legs 31, 32 will be swung downwards at substantially the same rate that the lower end 24 of the single leg 21 moves downwards.

Means are provided for releasably retaining the legs 21, 31, and 32 in selected position of angularity with respect to each other and consequently in any of a plurality of optionally selectable positions so as to make it possible for the operator to support the body 16 at whatever elevation might be most convenient. For this purpose, a rod 56 is connected at one end to each of the legs 31, 32 adjacent the lower end of the latter. The other ends of both of the rods 56 are connected to a catch mechanism, indicated in its entirety at 57 and illustrated in detail in Figures 15 and 16. Slidably mounted upon the leg 21 adjacent its lower end are the two parts 58 and 59 of the latch mechanism 57. Each of these parts 58, 59 comprises a plate 61, the lateral edges 62 of which are bent downwards around the laterally extending flanges 63 of the two cooperative angle members whose vertically extending flanges 64 are secured together in face-to-face abutment to define the lower end 24 of the leg 21. The edges 62 of the plate 61 are relatively loosely fitted upon the flanges 63, however, so that both parts 58 and 59 are free to slide longitudinally along the lower end of the leg 21. The lower part 59 of the latch 57 is adapted to be releasably anchored in any of a plurality of optionally selectable positions by means of a pin 66 carried at the outer end of a lever 67 which is mounted upon the latch part 59 for rocking movement in such a manner that the end of the lever 67 to which the pin 66 is secured can be lowered away from the horizontal flange part of the leg 21 by pressing upwardly against the opposite end 68 of the lever 67. This mounting is easily attained by loosely fitting the lever 67 upon a pin 69 rigid with the latch part 59 and arranging a coil spring 71 under compression between the lever 67 and the head 72 of the pin 69. The end of the lever 67 which carries the pin 66 extends from the latch part 59 toward the latch part 58, preferably so far that the pin 66 is clear of the latch part 59 upon which it

is mounted. The pin 66 may be extended through any one of a plurality of holes 73 in one of the horizontal flanges of the leg 21, the spring 71 serving for the releasable retention of the pin 66 in that hole until the operator, by depressing the end 68 of the lever 67, withdraws the pin 66 from that hole, thus enabling her to slide the latch part 59 along the leg 21 until the pin 66 is in registry with another of the holes 73. In this manner, the latch part 59 may be releasably anchored in any selected position along the lower part of the leg 21.

The rods 56 are attached to downwardly extending tabs 81 rigid with the other latch part 58, and upon the upper surface of the latch part 58 a lever 82 is pivotally mounted as by a rivet or pin 83 extending upwards from the plate 61. A coil spring 84 extending laterally from the inner end of the lever 82 and under tension between it and a pin 86 rigid with the plate 61 urges the lever 82 to rotate clockwise, as viewed upon Figure 15, about its pivot pin 83. The other end of the lever 82 is provided with a notch 87 in one lateral edge within which the upper end of the pin 66 of the other latch part 59 is adapted to seat, the spring 84 serving to retain the lever 82 in that position within which the pin 66 is seated in the notch 87. However, an upwardly extending tab 88 on the end of the lever 82 within which the notch 87 is provided, facilitates the lateral movement of the lever 82 about its pin 83, which permits the lever to be released from the pin 66. Thus it may be seen that the operator may release the latch part 58 to which the rods 56 are connected from the latch part 59 so that the latch part 58 may be slid along the leg 21 without releasing the latch part 59 from its selected position on the leg 21 below the latch part 58.

Consequently, when the operator desires to fold the ironing board, it is necessary merely to release the lever 82 from the pin 66, thus permitting the latch part 58 to slide upwardly along the leg 21, as is necessary for the lower ends of the legs 31 and 32 to move further away from the lower end of the leg 21 in their folding movement toward the body 16. This, however, does not release the lower latch part 59 and consequently does not alter the position of the pin 66, with the result that when the operator again desires to erect the board to its operative position, it is necessary merely to swing the legs away from the board, and the thrust which the legs 31 and 32 will thus exert upon the rods 56 will cause the latch part 58 to slide downwards along the leg 21 until the rounded end 91 of the lever 82 engages the pin 66, causing the lever 82 to move laterally and thereby permitting the spring 84 to engage the lever 82 upon the pin 66 when its notch 87 comes into registry therewith. Therefore, the board is caused to be erected at the same position as previously used unless, of course, the operator has in the meantime changed the position of the lower latch part 59 upon the leg.

Means are provided for spreading the lower ends of the legs 31 and 32 more widely apart as they are swung downwards to their operating position, and for drawing them laterally inwards toward each other as they are folded toward their collapsed position. Another brace rod 101 is associated with each of the legs 31 and 32, the lower end of the rod 101 being secured to the associated leg adjacent its lower end. Each of these brace rods extends upwards and angularly inwards from the associated leg 31, 32 so that its

upper end can be attached to the single leg 21. An important consideration in this connection is that the point of attachment of each of the rods 101 of the leg 21 is offset from the axis of the rod 36, the direction of such offsetting being from the pivot rod 36 toward the lower end 24 of the leg 21. Because of this arrangement, as the leg 21 swings upward from that position in which it is illustrated in Figure 1, it imposes tension upon both brace rods 101, causing the lower ends of the legs 31 and 32 to be drawn laterally inwards as they move upwards toward the body 16. Inasmuch as the legs are pivotally connected intermediate their ends to the pivot rod 36, the upper ends of the legs 31 and 32 will move farther apart as they slide longitudinally along the body 16 toward the pointed end 18; and it is on this account that the tracks or guide rods 48 are given the arcuate divergent form described hereinabove.

Conversely, when the legs 21, 31, and 32 move away from the board, i. e., from their folded toward their operating position, the leg 21 will impose compression upon both brace rods 101, with the result that they will force the lower ends of both legs 31 and 32 apart as they swing downwards into their position illustrated in Figure 1.

Consequently, when the ironing board is erected, i. e., in operative position, the legs 31 and 32 are widely spread, so effectively increasing the area of the base of support of the device that it is possessed of an ample degree of lateral stability; and yet when the legs are folded, the lower ends of the legs 31 and 32 are much more closely adjacent each other, in fact, so closely adjacent that they do not require a space for their storage any wider than that required by any other part of the ironing board.

Since the lower ends of the legs 31 and 32 move laterally inwards and outwards as hereinabove described, and since the rods 101 partake of much the same type of movement, means are provided for permitting pivotal movement of the upper ends of the rods 101 about axes parallel to the single leg 21. However, in the modification presently being described, it is most convenient to attach the upper ends of the rods 101 to the downwardly extending flange 64 of the associated part of the leg 21; and since this flange extends in the plane which includes the axis about which the upper end of the associated rod 101 must rotate as the associated leg 31, 32 partakes of the described lateral movement, the necessary pivotal movement of the upper ends of the rods 101 is most easily attained by the simple expedient of fitting an eye 102 at the upper end of each rod 101 upon a pin 103 rigid with the flange 64, as best shown in Figure 3. However, the fit between each eye 102 and its associated pin 103 should be sufficiently loose to permit the necessary lateral pivotal movement of the rod 101 as its associated leg 31, 32 moves laterally.

Figure 4 illustrates a convenient and inexpensive anti-friction foot for the lower end of the single leg 21. A pair of washers 106 of resilient material are secured to the outer faces of the downwardly extending flanges 64 of the two angle members which cooperate in defining the leg 21. A rivet or other suitable pin 107 extends through both washers 106 and through the flanges 64. So closely adjacent the extreme lower end of the leg 21 are these washers 106 mounted, that they extend beyond the corner described by the end edges and the lower lateral edges of the flanges

64, with the result that the resilient material of which the washers 106 are formed serves as the supporting foot at the lower end of the leg 21.

Referring now to the modification illustrated in Figures 6 to 10, inclusive, here again the body 111 is supported by means of a single leg 112 pivotally mounted as by a bracket 113 adjacent the broad end 114 of the body 111, and by a pair of legs 116, 117 straddling the single leg 112 and mounted for longitudinal sliding movement along the under surface of the body 111 between the bracket 113 and the opposite, pointed end 118 of the body. In this instance, however, the upper ends of the legs 116 and 117 partake of straight line movement in paths parallel to each other and parallel to the longitudinal axis of the body 111; and consequently the tracks 121 by which the upper ends of the legs 116 and 117 are connected to the board are straight rather than arcuate as in the previously described modification.

Each track 121 comprises a channel section, best illustrated in Figure 8, one flange 122 being secured to the under surface of the body 111 and the opposite flange 123 being maintained in spaced parallel relationship thereunder by the downwardly extending web portion 124 of the channel section. The two tracks 121 are mounted in opposition to each other with their open faces toward each other so that a rod 126 of round section can be slidably mounted under the board by having one end seated within each of the channel-shaped tracks 121. A plate 127 is rigidly secured to the rod 126 as by welding, and to this plate 127, preferably adjacent its ends and spaced inwardly only a slight distance from the associated track 121, are pivotally secured the upper ends of the legs 116 and 117 as by pins 128.

Inasmuch as the distance between the upper ends of the legs 116 and 117 does not vary as they move longitudinally along the board, in order to attain the lateral adjustment of the legs 116 and 117 as they shift from one extreme position to the other, the present modification is arranged to permit the midportions of the legs 116 and 117 to move further apart as the legs are opened, and to move towards each other as the legs are collapsed. With this object in view, a relatively short rod 131 is pivoted as by a pin 132 to each leg 116 and 117 at that point between the ends of the leg which permits the rod 131 to have its other end slidably disposed within a tube 133 which is rigidly secured to the single leg 112. Both of the rods 131 are free to rotate within the tube 133, and accordingly these rods 131 provide the pivotal interconnection of the mid section of each of the legs 116, 117 to the mid section of the single leg 112, which is necessary to permit the legs 116 and 117 to partake of the pivotal movement with respect to the single leg 112 which accomplishes the movement of the legs toward and away from the body 111. However, since the two rods 131 are independent of each other and are also free to slide longitudinally with respect to the pivot tube 133, they also permit the legs 116, 117 to slide apart as they pivot away from the body and to draw toward each other as they move toward the body 111. Moreover, since the pins 132 extend through the inwardly extending flanges of the legs 116 and 117, respectively, the axes of these pins are perpendicular to the plane within which both of the legs 116 and 117 lie. Consequently, this pivotal connection of the legs

116 and 117 to the rods 132 permits the legs 116 and 117 to partake of the rocking movement within the said plane and about the axes of the pins 132 which coincides with the spreading of the legs in pivotal movement about the axes of the pins 128 whereby the upper ends of the legs 116 and 117 are connected to the rod 126 (see Fig. 8), the ends of which slide within the opposed tracks 121 on the under surface of the body 111.

The means for attaining this lateral movement of the legs 116, 117 preferably is the same as that described in the previously described modification, i. e., by means of a brace rod 141 associated with each leg 116, 117 and connected at its lower end adjacent the lower end of the associated leg. The upper ends of both brace rods 141 are connected to the single leg 112 at a point offset from the axis of the rods 131 and their pivot tube 133, the direction of such offset being toward the lower end of the leg 112, as in the previously described modification.

As best illustrated in Figure 10, a slightly modified form of catch is provided for the releasable retention of the legs 116 and 117 in selected degree of angularity with respect to the single leg 112 so as to retain the body 111 of the ironing board at selected elevation. This catch, which is indicated in its entirety at 142, comprises a plate 143, the lateral edges 144 of which are bent so as to embrace the lateral edges of the horizontal flanges of the angle members defining the leg 112 and thereby slidably retain the plate 143 upon the upper surface of the leg 112 adjacent its lower end. Downturned ears or tabs 146 of the plate 143 have the associated ends of rods 147 pivotally connected thereto, the other ends of these rods being pivotally connected to the legs 116 and 117 so as to maintain the legs 116 and 117 in selected position with respect to the leg 112 when the plate 143 is anchored to the latter.

A resiliently flexible strip 151 is pivotally mounted upon the upper surface of the plate 143 as by a rivet 152; and an anchoring pin 153 extends downwards from the strip 151 through an arcuate slot 154 in the plate 143 so that it can be selectively seated within any of a plurality of holes 156 at spaced intervals along the leg 112. The slot 154 is provided, rather than a hole, to which the pin 153 is more closely fitted, inasmuch as it permits the strip 151 to be rotated laterally about the rivet 152 after the pin 153 has been withdrawn from a hole 156, with the result that the latch 142 will be free to slide along the leg 112 without danger of its pin 153 becoming engaged in another hole 156 until the strip 151 is swung back to its latching position, as illustrated in Figure 10.

Convenience is afforded in extending and collapsing the legs of the ironing board by an extension 161 rigid with the broad end 114 of the body 111, of sufficient length to support the folded ironing board standing on end with the lower ends of the folded legs 116 and 117 elevated above the supporting surface. Since the legs partake of a sliding movement as they are swung away from the body toward their open position, the board would have to be balanced on one of the legs 116, 117 as the opening movement occurs were it not for the presence of the extension 161.

Figures 11 to 14, inclusive, illustrate a still further modified form of vertically adjustable folding ironing board embodying the principles of the present invention. In this instance, also, the

upper ends of the pair of legs 171 and 172 traverse straight line path parallel to each other and parallel to the major axis of the body 173 of the ironing board. Hence, the tracks 174 guiding the upper ends of the legs 171 and 172 are straight and parallel. The legs 171 and 172 straddle the single leg 176 and are pivotally connected thereto as by a transverse rod 177 having flanges 178 at its ends to which the legs 171 and 172 are pivoted as by pins 179. Hence, the distance between the midportions of the legs 171 and 172 is invariable also, and the sliding of the lower ends of the legs, in accordance with the principles of the present invention, is attained as the result of the flexibility of the upper portions of the legs 171 and 172. Consequently, although the legs 171 and 172 from the pivot rod 177 downwards are of angular section, as indicated at 181, the transversely extending flanges 182 of the legs terminate just below the pivot rod 177, with the result that, from the upper ends of the flanges 182 upwards, the legs 171 and 172 are flat strips capable of bending laterally so as to permit the lower ends of the legs to spread, as indicated in Figure 13.

As in the previously described modifications, the spreading and drawing together of the legs 171 and 172 is attained by rods 186, the lower ends of which are connected to the legs 171 and 172 adjacent their lower ends and the upper ends of which are connected to the single leg 176 offset toward the lower end of the leg 176 from the axis of the pins 179 which constitute the axis of pivotal movement of the legs 171 and 172 with respect to the single leg 176.

A slightly modified form of interconnection between the spreading rods and the single leg is illustrated in detail in Figure 14. The upper end of each rod 186 is pivotally connected to an angle bracket 187 by a pin 188, the axis of which is substantially parallel to the major axis of the leg 176. Both brackets 187 are pivotally connected as by a pin 189 common to both and extending through the vertical flanges of the angle members constituting the single leg 176. The pin 189, therefore, permits the rods 186 to move freely in the pivotal movement thereof which is necessary as the angle varies between the leg 176 and the plane occupied by the pair of legs 171 and 172; and the pins 188 permit the rods 186 to pivot freely about axes parallel to the single leg 176 as the legs 171 and 172 spread apart and are drawn toward each other.

I claim:

1. As a new article of manufacture, a folding ironing board comprising a body, a leg pivotally mounted at its upper end adjacent one end of said body, a pair of legs extending in a plane intersected by said first-mentioned leg and arranged in straddling relation thereto, means spaced toward the other end of said body from the pivotal connection of said first-mentioned leg thereto and connecting the upper end of each of said legs of said pair of legs to said body for pivotal movement with respect thereto about a transverse axis and for movement longitudinally of said body in straight parallel paths extending longitudinally of said body, means connecting each of said legs of said pair intermediate its ends to said first-mentioned leg intermediate its ends for pivotal movement about a transverse axis and for pivotal movement about an axis perpendicular to said plane, said means for pivotally interconnecting said legs also being slideable in the direction of said transverse axis

whereby the distance between the lower ends of the legs of said pair is variable, and a rod associated with each of said legs of said pair and pivoted thereto at one end of said rod for movement about an axis adjacent the lower end of that leg, and at the other end of said rod to said first-mentioned leg for movement about an axis parallel to and offset below said transverse axis of pivotal interconnection of said pair of legs to said first-mentioned leg, said other end of each of said rods also being pivotally connected to said first-mentioned leg for movement about an axis substantially perpendicular to said transverse axis of pivotal interconnection of said pair of legs to said first-mentioned leg.

2. As a new article of manufacture, a folding ironing board comprising a body, a leg pivotally mounted at its upper end adjacent one end of said body, a pair of legs extending in a plane intersected by said first-mentioned leg and arranged in straddling relation thereto, means spaced toward the other end of said body from the pivotal connection of said first-mentioned leg thereto and connecting the upper end of each of said legs of said pair of legs to said body for pivotal movement with respect thereto about a transverse axis and for movement longitudinally of said body in straight parallel paths extending longitudinally of said body, means connecting each of said legs of said pair intermediate its ends to said first-mentioned leg intermediate its ends for pivotal movement about a transverse axis and for pivotal movement about an axis perpendicular to said plane, said means for pivotally interconnecting said legs also being slideable in the direction of said transverse axis whereby the distance between the lower ends of the legs of said pair is variable, a rod associ-

ated with each of said legs of said pair and pivoted thereto at one end of said rod for movement about an axis adjacent the lower end of that leg, and at the other end of said rod to said first-mentioned leg for movement about an axis parallel to and offset below said transverse axis of pivotal interconnection of said pair of legs to said first-mentioned leg, said other end of each of said rods also being pivotally connected to said first-mentioned leg for movement about an axis substantially perpendicular to said transverse axis of pivotal interconnection of said pair of legs to said first-mentioned leg, and releasable means for locking the legs of said pair in any one of a plurality of optional positions of rotational adjustment about said transverse axis for releasably retaining said body at any one of a plurality of optional elevations.

3. In an ironing board having supports at least one of which constitutes a pair of legs which spread to give lateral stability as said legs are moved to supporting position, a connection between said board and said legs, and a telescoping rod and tube arrangement for providing interconnection between said legs to permit said legs to spread apart and retract.

ROXTON C. MCKINNIE.
